7 Claims. (Cl. 18—15)

The present invention relates to the manufacture of sheet or films from thermoplastic film-forming materials, and more particularly to an apparatus for quenching of a continuous shaped stream or sheet of film-forming material without distorting the same.

In a conventional procedure for forming sheets or films, as for example from polypropylene or polyethylene, molten film-forming material is extruded as a continuous shaped stream or sheet of substantially uniform thickness and then quenched within a bath of cool water or other suitable liquid. The quenched sheet is dried and then oriented by being stretched along one or both of its axes while in a heated condition, to improve the physical and perhaps the optical properties thereof. It has been found, however, that during the quenching stage variations are induced in the gage or thickness of the sheet along its length. Since these areas of different thickness do not respond alike during the subsequent heating and stretching operation, the stretched sheet exhibits gage variations which are now magnified. Further, in view of the differential molecular orientation effected during the stretching operation, the resulting sheet possesses non-uniform physical and/or optical properties.

Various proposals have been made for eliminating or at least minimizing the above described problem. Such proposals generally involve the use of baffles, shields and deflectors as well as specifically designed jets or manifolds for controlling the direction and movement of the cooling liquid. None of these proposals, however, have proven to be satisfactory. Accordingly, a primary object of this invention is to provide a new or generally improved and more satisfactory apparatus for quenching of shaped streams or sheets of molten film-forming material.

A further object is the provision of an improved apparatus for quenching an extruded stream of molten film-forming material by subjecting the opposite sides thereof to high volume, low velocity flows of cooling liquid.

A still further object is the provision of an improved apparatus in which opposite sides of a continuous shaped stream of molten film-forming material are quenched by high volume, low velocity streams of cooling liquid maintained at substantially the same temperature.

These and other objects and advantages of the invention will be apparent from the following description and accompanying drawing in which:

FIGURE 1 is a plan view of a portion of the quenching apparatus of the present invention; and

FIGURE 2 is a vertical section taken longitudinally of the structure shown in FIGURE 1.

The present invention is based upon my discovery that gage variations induced along the length of a shaped stream of molten film-forming material during the quenching thereof are due primarily to: (1) changes in the melt draw-down ratio of the extruded film-forming material, and (2) changes in the melt draw distance, or in other words, changes in the length of that portion of the extruded stream of film-forming material which is subjected to a drawing action.

The melt draw-down ratio can be best defined as the ratio of the take-off speed or the speed at which the quenched sheet is withdrawn from the quench bath to the velocity of the molten film-forming material as it issues from an extrusion nozzle. Changes in the melt draw-down ratio can be minimized by employing take-up rolls

2

which are capable of removing the quenched sheet from the quench bath at a predetermined metered rate of speed and/or by using an extrusion apparatus which provides for a substantially uniform delivery of film-forming material to the extrusion nozzle. The present invention is therefore particularly concerned with the problem of eliminating or minimizing changes in the melt draw-down distance.

The melt draw distance is defined as the distance from the extrusion nozzle to the point below the surface of the quench bath at which the shaped stream of film-forming material solidifies. This point at which solidification of the shaped stream or sheet of film-forming first occurs is generally visible as a "frost line" which extends across the sheet. The location of the "frost line" is dependent upon such factors as the temperature and specific heat of the particular film-forming material employed, the distance between the extrusion nozzle and the surface of the quench bath, the temperature of the quenching or cooling liquid, and the gage of the sheet or film which is being formed. Basically, the present invention is directed to an apparatus in which the distance between the extrusion nozzle and the surface of the quench bath and the temperature of the quenching liquid are maintained substantially constant throughout the film-forming operation.

In accordance with the method practiced with the apparatus of the present invention, a shaped stream or sheet of molten film-forming material is quenched by high volume, low velocity streams of cooling liquid which sweep along the opposite sides of the shaped sheet of film-forming material, and in a direction opposite to the movement of such sheet, and are then discharged. In this manner localized heating of the quenching liquid is avoided so that successive portions of the shaped stream or sheet of film-forming material are quenched by cooling liquid which is at substantially a constant temperature. With continued advancement of the quenched sheet, its opposite sides are swept by high volume, high velocity streams of cooling liquid which provide for a more efficient quenching action of the sheet throughout its thickness. Subsequently, the quenched sheet is withdrawn from the quench bath at a metered rate of speed, during which movement, its opposite surfaces are again subjected to high volume, low velocity streams of cooling liquid. As more fully described hereafter, the surface area of the quench bath employed in the present method is maintained at a minimum to prevent any build-up of waves or other surface fluctuations as the shaped sheet of film-forming material enters and leaves the quench bath.

The apparatus for practicing the above described method includes a quench tank for containing a cooling liquid, a nozzle for extruding a uniform shaped stream or sheet of film-forming material into the quench tank and rolls for removing the quenched sheet from the tank at a metered rate of speed. Within the area below the metering rolls, the quench tank includes means for directing a high volume, low velocity flow of cooling liquid against opposite sides of the sheet. This cooling liquid flows in a direction opposite to the travel of the sheet and is withdrawn from opposite sides thereof, as high volume, low velocity streams, in the area of the tank below the extrusion nozzle.

The apparatus of the present invention is adapted for use with thermoplastic, polymeric film-forming materials which may be shaped into a desired film or sheet by melt casting procedures. Further, the sheets or films produced in accordance with the present invention may be of uniform or varying cross-section or may be provided with thickened or beaded portions along its opposite longitudinal edges.

With reference to the drawing, the apparatus of the

present invention includes a nozzle or die 5 for extruding a shaped stream or sheet 7 of molten film-forming material, a quench tank 9 for containing a cooling liquid 11, such as water, for quenching the shaped stream of film-forming material into a solid sheet or film 13, and a pair of nip rolls 15 for withdrawing the sheet 13 from the quench tank 9 at a uniform rate of speed.

The tank 9 may be of any desired configuration and, as illustrated, includes a bottom wall 17, side walls 19 and end walls 21. Positioned within the tank 9 and directly below the nip rolls 15 are a pair of spaced chambers or conduits 23 and 25, of which opposing walls 27 and 29 are perforated as shown at 31. Cooling liquid 11 is delivered into the chambers 23 and 25 by pipes 33 which are in turn connected to a suitable supply source, not shown.

The opposite end of the tank 9 is similar to that described above and includes a pair of spaced chambers or conduits 35 and 37 positioned below the nozzle 5 and having opposed walls 39 and 41 perforated, as shown at 43. Pipes 45 are disposed within the chambers 35 and 37 and are connected to a common discharge conduit 47 whereby cooling liquid 11 withdrawn through chambers 35 and 37 may be refrigerated and returned to the quench tank 9 through chambers 23 and 25.

As illustrated the chambers 25 and 37 terminate above the bottom wall 17 of the tank 9. A divider or partition 49 extends between the lower ends of these chambers 25 and 37 and includes an access door 51 and door lock 53. Rolls 55 are positioned adjacent to the bottom wall of the tank 9, generally in alignment with the spaces between cooperating pairs of chambers, for guiding the sheet 13 along a desired path through the quench tank.

In use, cooling liquid 11 is delivered through pipes 33 and the perforated walls of chambers 23 and 25 to substantially fill the tank 9, including the portion thereof located above the divider 49. Molten film-forming material is then extruded from the nozzle 5 as a shaped stream 7 which travels downwardly into the quench tank 9 in-between the chambers 35 and 37. As the stream 7 enters the cooling liquid, at least its surfaces are rapidly set or quenched to provide the continuous sheet or film 13. By opening the access door 51, the sheet 13 may be readily laced around the rolls 55 and then upwardly in-between the chambers 23 and 25 to the metering rolls 15. The access door 51 is then locked in its closed position after which the cooling liquid above the divider 49 may be removed by any conventional pump means.

With the apparatus laced as described above, cooling liquid 11 is continuously delivered into the chambers 23 and 25 and flows therefrom through the perforations 31. As indicated by arrows 57 the cooling liquid 11 flows along opposite sides of and in a direction counter to that of the quenched sheet 13. Between the chambers 35 and 37, the cooling liquid 11 sweeps along the opposite sides of the shaped stream of film-forming material as it initially enters the quenching tank and is then discharged through the chamber perforations 43 and pipes 45.

It will be apparent that as the cooling liquid sweeps along the opposite side of the shaped stream of film-forming material, heat is extracted therefrom to at least set the surface portions thereof into the form of sheet 13. Further, following this sweeping movement along the sheet 7, the cooling liquid is continuously discharged into the chambers 35 and 37. As a result, the successive portions of the shaped stream of film-forming material are solidified at substantially the same point within the quench tank; that is, the distance between the extrusion nozzle and the "frost line" across the sheet or film 13 remains constant throughout the method.

The number, size, and arrangement of the perforations 31 and 43 formed in the opposing walls of the respective pairs of chambers may be varied to suit particular operating conditions. The perforations 31 formed in the

opposed chamber walls 27 and 29 preferably provide for a high volume, low velocity flow of equal amounts of cooling liquid 11 to the opposite sides of the sheet of film 13. Similarly, the perforations 43 in the opposed chamber walls 39 and 41 must facilitate a high volume, low velocity flow of liquid 11 away from opposite side of the sheet after it has performed its quenching function.

While the perforations 31 preferably define a total open area which is substantially equal to that provided by the perforations 43, such open area should be greater than the cross sectional area of passageway 59 which is formed by the bottom wall 17, the divider 49 and the adjacent portions of the tank side walls 19. With this arrangement, a comparatively high volume, high velocity flow of cooling liquid 11 is provided within the passageway 59. Since this flow runs counter to the direction of travel of the sheet 13, any liquid carried by and along with the sheet 13 is swept clear of the opposite surfaces to thus provide for a more uniform, rapid and efficient quenching action.

It will be noted that with the delivery of cooling liquid as described above, bubbles of air or other gases contained therein are well removed from the area in which the molten stream of film-forming material first enters the quench tank and therefore are not able to mar or otherwise effect the surfaces thereof.

Aside from satisfying easy lacing operations, the spacing between the cooperating chambers of each pair of chambers should be kept to a minimum. In this manner, the small surface areas of the cooling liquid at the entrance and exit portions of the quench tank minimize any build-up of surface waves or other fluctuations.

As illustrated, the chambers 23 and 35 are substantially equal in height to the chambers 25 and 37. If desired, the lower portions of the chamber walls 27 may be perforated, as indicated by broken lines, to permit additional cooling liquid to be delivered into the passageway 59 and subsequently discharged through similar perforations formed in the lower portion of the chamber wall 39.

It is to be understood that changes and variations may be made without departing from the spirit and scope of the invention as defined in the appended claims.

I claim:

1. Apparatus for use in the manufacture of films including a tank having a bottom wall and upright side and end walls, a pair of spaced upright, perforated partitions disposed adjacent to each of said end walls and extending between the side walls thereof, the lower ends of adjacent partitions of said pairs of partitions terminating above the bottom wall of said tank, a divider plate extending between the lower ends of said adjacent partitions and the side walls of said tank, means for delivering a cooling liquid through the perforations of one pair of said partitions, means for withdrawing cooling liquid through the perforations of the other of said pair of partitions, means for extruding a sheet of molten film-forming material into the cooling liquid in-between the partitions of said other pair of partitions, means for withdrawing the cooled sheet of film-forming material from the cooling liquid between the partition of said one pair of partitions, and means for directing the cooled sheet of film-forming material between the bottom wall of said tank and said divider as the sheet is advanced in a direction counter to the flow of cooling liquid.
2. In an apparatus for use in the manufacture of continuous films, a tank having a bottom wall and upright side and end walls, a first pair of spaced chambers extending between the side walls of said tank adjacent to one end wall thereof, a second pair of spaced chambers extending between the side walls of said tank adjacent to the opposite end wall thereof the lower ends of adjacent chambers of said first and second pairs of chambers terminating above the bottom wall of said tank, a partition extending between said lower ends of said adjacent chambers and cooperating with the bottom and side walls

of said tank to form a passageway which provides a continuous passage between said first and second pairs of chambers, opposing walls of each pair of said chambers having similar perforations, means for delivering a cooling liquid through the perforated walls of said first pair of chambers and into the space therebetween, and means for withdrawing cooling liquid from the space between said second pair of chambers through the perforated walls thereof.

3. Apparatus as defined in claim 2 wherein the perforated areas of said first and second pairs of chambers are substantially equal but greater than the cross sectional area of said passageway.

4. Apparatus as defined in claim 2 further including means for delivering a shaped sheet of molten film-forming material between said second pair of chambers and into the cooling liquid to quench the same, means for withdrawing the quenched sheet of film-forming material from the cooling liquid between said first pair of chambers, and means within said tank for directing the quenched sheet along said passageway.

5. Apparatus as defined in claim 4 further including a door in said partition for use in lacing the sheet through said passageway.

6. Apparatus for use in the manufacture of films including a tank having a bottom wall and upright side and end walls, a pair of conduits disposed adjacent to each of said end walls and extending between the side walls of said tank, the conduits of each pair of conduits being spaced from each other, means for delivering a liquid to one pair of said conduits, a plurality of openings formed in opposing surfaces of said one pair of conduits for discharging liquid therefrom and into the space between such conduits, a passageway for directing the liquid from the space between said one pair of conduits

5 to the space between the other of said pair of conduits, a plurality of openings formed in opposing surfaces of said other pair of conduits for withdrawing liquid from the space therebetween, means for removing liquid from said other pair of conduits, the surface area included by the openings in each pairs of conduits being substantially equal, means for extruding a shaped stream of film-forming material into the space between said other pair of conduits and thereby solidify the same into a film by the liquid contained therein, and means for withdrawing the film from the space between the said one pair of conduits.

10 7. Apparatus as defined in claim 6 wherein the surface area included by the openings of each pair of conduits is greater than the cross-sectional area of said passageway.
